UNITED STATES PATENT OFFICE

CHARLES F. ABBOTT, OF NEW YORK, N. Y.

IMPROVEMENT IN VENTILATORS FOR HATS.

Specification forming part of Letters Patent No. **174,998**, dated March 21, 1876; application filed January 22, 1876.

To all whom it may concern:

Be it known that I, CHARLES F. ABBOTT, of the city, county, and State of New York, have invented an Improvement in Ventilators for Hats, of which the following is a specification:

This invention relates to that class of ventilators for hats in which a piece of corrugated leather or like material is interposed between the sweat-band and the body of the hat at the front of the latter, in such manner as to provide passages through which, when the hat is worn, air can pass up in contact with the forehead of the wearer to the interior of the hat, thereby not only cooling the head, but also, by the contact of the upward current of air, the forehead of the wearer aforesaid—it being usual to provide a hole or orifice in the crown of the hat, to permit the escape of heated air and insure the continuity of the current so long as the hat remains upon the head.

Assuch ventilators have been hitherto made, the corrugations have been kept intact by means of strips of cloth pasted or cemented upon one side of the corrugated leather, to prevent the spreading or elongation of the same. This construction of the corrugated ventilating-piece is expensive and unreliable, requiring comparatively high-priced and skilled labor in its manufacture, and the strips being extremely liable to stretch or become detached.

The purpose of my invention is to obviate these drawbacks by providing a ventilating-piece which may be quickly and strongly made by extremely cheap and almost wholly unskilled labor, and which, moreover, from the durability arising from its peculiar construction, will be as durable as the hat to which it may be applied.

To this end my said invention comprises a flexible corrugated ventilating-piece, having one or more wires passed transversely through its corrugations and made fast at each end, in such manner as to securely hold the corrugations against all tendency to flatten or spread out, the said wire or wires being, from the mode of attachment, not liable to displacement or derangement from any vicissitude of use.

Figure 1 is a central vertical sectional view of a hat fitted with a ventilating-piece made according to my invention. Fig. 2 is a horizontal sectional view of the same. Fig. 3 is a side view, representing the corrugated ventilating-piece made according to my invention, as aforesaid, detached; and Fig. 4 is an edge view of the same on a larger scale.

A is the hat, provided, in the usual manner, with an orifice, *a*, in the crown. B is the sweat-band, disposed in the usual place adjacent to the brim. C is the corrugated ventilating-piece, which, when applied to use, is interposed between the lower part of the front of the hat and the adjacent front portion of the sweat-band, as shown in Figs. 1 and 2. The corrugations of the ventilating-piece C form passages *a'*, through which air may pass up at the front of the hat into its interior, and thence out through the orifice *a*, when the hat is worn. In the fabrication of the piece C the leather or like material is cut to proper size and contour, and is then crimped or corrugated by being passed between grooved rollers, or by other suitable means, the corrugations being transverse to the length of the piece. When thus corrugated it is necessary to provide against the flattening of the corrugations by the longitudinal stretching or elongation of the piece, as such flattening would close the passages *a'* and destroy the utility of the device. In the means adopted to prevent this lies the gist of my invention.

When the ventilating-piece C has been corrugated, as just hereinbefore set forth, I perforate the same from end to end through its corrugations, the perforations being, of course, in line with each other and transverse to the corrugations. Through this line of perforations I pass a wire, *c*, and, after fastening one end of said wire to one of the ends *b'* of the piece C, I draw the wire snugly enough to cause the requisite bulge or prominence of the corrugations, and then fasten the remaining end of the wire to the opposite end of the piece C. The fastening of the ends of the wire, as aforesaid, may be done by passing the same through the ends *b'* of the piece C, and then folding, turning over, or clamping the same by the use of pliers or other suitable implement.

The ventilating-piece C may have but one of the wires c, as shown in Fig. 1, or two, as shown in Fig. 4, or even more, if preferred. Inasmuch as the wires or wires are incapable of stretching it follows that the elongation of the ventilating-piece is impossible. Inasmuch as the clinched or folded ends of the wire hold firmly in the material of which the ventilating-piece is made, and the length of said wire is firmly sustained in the corrugations, it follows that the detachment of the wire, and the loosening of the corrugations that would result therefrom, is effectually guarded against, and inasmuch as the attachment of the wire is a matter simple and easy for even an unskilled operative, the cost of manufacturing the ventilating-piece is very slight.

It will of course be understood that the ventilating-piece C, as thus constructed, may be secured in place in the hat by any suitable means, and that the wire c has a diameter so

small as to cause no appreciable obstruction to the passage of air through the passages a', provided by the corrugations in said ventilating-piece. The perforations in the corrugations aforesaid, for the reception of the wire or wires, may be made by any suitable means; but in practice I propose to use the implement shown and described in my application of even date with this for a patent on improvements in apparatus for making corrugated ventilators for hats.

What I claim as my invention is—

The flexible corrugated ventilating-piece C, having a wire or wires, c, passed through its corrugations and fastened at each end, substantially as and for the purpose set forth.

CHAS. F. ABBOTT.
